UNITED STATES PATENT OFFICE.

JOHN F. O'CONNOR, OF CHICAGO, ILLINOIS, ASSIGNOR, BY MESNE ASSIGNMENTS, TO
W. H. MINER, INC., A CORPORATION OF DELAWARE.

CENTER BEARING.

Application filed June 25, 1923. Serial No. 647,436.

This invention relates to improvements in center bearings.

In the operation of railroads, it has been found advisable to so connect the body and truck bolsters of a car that the same cannot be separated vertically in case of collision or derailment, as this effectively prevents or minimizes the turning over or telescoping of the cars. It has been the usual practice to make use of a sectional pivot or king pin to lock the parts together but much difficulty has been experienced in a great many instances in applying such locking means, especially in the case of a six-wheel truck; and particularly dining, buffet and baggage cars, for the reason that the central axle of the six-wheel truck is located immediately below the pivotal center and it is impossible to obtain access from above the bolster through the car floor on account of the stoves or other fixtures of the car being located directly over the bolsters.

Certain railroads also prefer using cast body bolsters having a continuous top web over the king pin opening and therefore in such cars having six-wheel trucks, it is impossible to insert or withdraw, vertically, the king pin or other type of locking device unless the truck is completely dismantled for that purpose, which is prohibitive from a practical standpoint.

One object of the invention is to provide a locking connection for bolsters of an efficient type, comprising interlocking center bearing plates, thereby doing away entirely with the necessity for a locking king pin or other similar pivotal fastening device.

Another object of the invention is the provision of an improved center bearing for railroad cars wherein the parts of the bearing permanently attached to the body and truck bolsters are effectively interlocked by readily detachable means located entirely within the space between the bolsters and adapted to be applied by being inserted between the lower face of the body bolster and the upper face of the truck bolster, thereby especially adapting the device for cars having a truck so constructed that access from above and below the bearing is practically impossible.

In the drawing forming a part of this specification, Figure 1 is a vertical, sectional view through the center portion of the body and truck bolsters of a car, showing my im-

provements in connection therewith. Fig. 2 is a horizontal, sectional view, corresponding substantially to the line 2-2 of Fig. 1. Fig. 3 is a view similar to Fig. 1, illustrating a different embodiment of the invention. Fig. 4 is a horizontal, sectional view corresponding substantially to the line 4-4 of Fig. 3. Fig. 5 is a view similar to Fig. 1 illustrating another embodiment of the invention. And Fig. 6 is a horizontal, sectional view corresponding substantially to the line 6-6 of Fig. 5.

Referring first to the construction illustrated in Figs. 1 and 2, 10 denotes the lower portion of a body bolster and 11 the upper portion of an opposed truck bolster. My improved device, as shown, comprises an upper center bearing member A; a lower center bearing member B; a pair of locking blocks C-C; and two pairs of locking pins D-D and E-E.

The upper member A is provided with a pair of side flanges 12 secured to the body bolster by rivets 13 or any other suitable fastening devices. The member A is provided with a downwardly projecting, hollow, cylindrical portion 14 having an annular, horizontally disposed, flange 15 at its lower side. The member B is also provided with a pair of side flanges 16 similar to the flanges 12, by which the same is secured to the truck bolster by rivets 17 or any other suitable fastening devices. The member B is provided with a continuous, vertical flange 18 of rectangular outline, thereby providing a rectangular opening 19 adapted to receive the blocks C.

The blocks C are of like construction, each being of generally rectangular outline and of a thickness equal to the height of the flange 18. Each of the blocks is cut out at one side to provide an arcuate recess 20 and an arcuate, horizontally disposed flange 21 overhanging the recess. When the parts are in assembled relation, the blocks are disposed within the recess 19 of the member B on opposite sides of the cylindrical portion 14 of the member A with the flange 15 of the latter disposed in the recesses 20 of the blocks and the flanges 21 of the blocks engaging over the flange 15 with the adjacent edges of the blocks slightly spaced apart. The blocks C are retained within the opening 19 of the lower member B by the pins D and E, received in grooves 22 and 23 formed

in the inner faces of the flange 18 and the opposed edges of the blocks C, each set of grooves 22 and 23 registering and forming a cylindrical recess when the parts are assembled. The rectangular flange 18 is provided with two openings 24 adjacent each of the corners thereof, each opening being aligned with a set of grooves 22 and 23 to permit the insertion of the pins D and E.

- 10 The pins E are provided with heads at one end adapted to abut the outer side of the flange 18 and are retained in position by cotters extending through the opposite ends thereof. The pins D are somewhat shorter than the distances between the pins E and are retained within the grooves 23 by the pins E extending transversely of and closing the openings 24 through which the pins D are inserted.

- 15 With the arrangement shown in Figs. 1 and 2, it will be seen that the center bearing section A may be assembled and interlocked with the section B by inserting the blocks C within the recess 19 of the member B with the flanges 21 engaging over the flange 15 of the member A and inserting the pins D and E in the proper openings, the pins D being first inserted. The pins D and E engage in the opposite grooves 23 and 22 of the blocks 20 and the flange 18 and effectively lock the blocks in position, the flanges 21 thereof overhanging the flange 15 and holding the sections A and B interlocked. In separating the members A and B the reverse procedure takes place as will be obvious.

- 25 Referring next to the construction illustrated in Figs. 3 and 4, 110 denotes the lower portion of the body bolster and 111 the upper portion of the truck bolster. The improved device, as shown in these figures, comprises an upper center bearing member A'; a lower center bearing member B'; and a series of ball bearings F'.

- 30 The upper member A' is provided with a flange 112 secured to the body bolster by rivets or any other suitable fastening devices. The lower member B' is also provided with a similar flange 116 secured to the truck bolster by rivets or any other suitable fastening devices. The member A' is provided with a central opening 130 surrounded by a downwardly projecting circular flange 114 having an annular groove 131 of semi-circular cross section on the inner face thereof.

- 35 The member B' is provided with an upwardly projecting circular flange 118 of smaller diameter than the flange 114, and is provided with an annular groove 113 of semi-circular cross section on the outer face thereof complementary to the groove 131. The flanges 114 and 118 are adapted to interfit with the grooves 131 and 113 thereof in alignment and forming, in effect, a raceway adapted to receive the balls F'. At op-

posite sides, the flange 114 of the member A' is provided with openings 133 of a size to permit the insertion of the balls F', the openings being closed by pipe plugs 134.

When the parts are in assembled relation with the balls F' in the raceway formed by the grooves 131 and 113, the parts A' and B' will be held interlocked, and vertical separation of the body and truck bolsters prevented. In addition to acting as a means for holding the center bearing in assembled relation, the balls F' act as anti-friction means thereby providing an anti-friction center bearing.

30 It will be evident that the center bearing member A' may be assembled and interlocked with the member B' by inserting the circular flange 116 within the circular flange 114, bringing the grooves 131 and 113 thereof into registration and inserting the series of balls F' within the raceway thus formed through either or both of the openings 133. When the raceway has been filled the openings 133 are closed by the plugs 134, thereby retaining the balls in place. To separate the members A' and B' it is merely necessary to remove the balls from the raceway, the same being withdrawn through the openings 133.

35 Referring next to the construction illustrated in Figs. 5 and 6, 210 denotes the lower portion of the body bolster and all the upper portion of the truck bolster. The improved device, as shown in these figures, comprises an upper center bearing member A²; a lower center bearing member B²; and a pair of locking elements or blocks G².

40 The upper member A² is provided with flanges 212 secured to the body bolster by rivets 213, or any other suitable fastening devices. The member A² is provided with a downwardly projecting, hollow cylindrical portion 214 having an annular, horizontally disposed, flange 215 at the lower end thereof. The lower member B² is also provided with flanges 216, similar to the flanges 212, secured to the truck bolster by rivets or any other suitable means. The upper surface of the member B² is recessed as indicated at 240 to receive the circular flange 215 of the member A², the recess 240 having a flat bottom, and corresponding in depth to the thickness of the flange 215 so that the upper face of the flange will lie flush with the upper face of the member B² and the lower surface of the cylindrical portion 214 of the member A² will bear on the flat bottom of the recess. The member B² also has an upstanding circular flange 218 in spaced relation to the cylindrical portion 214 of the member A², thereby providing a circular opening 219. The flange 218 is cut out at opposite inner sides, thus providing arcuate recesses as indicated at 220 and overhanging ledges 221. The flange 218 is cut out on

9645 9650 9655 9660 9665 9670 9675 9680 9685 9690 9695 9700 9705 9710 9715 9720 9725 9730 9735 9740 9745 9750 9

diametrically opposite sides to provide downwardly extending, radially disposed, openings 222 midway between the ends of the recesses 220.

5 The locking elements G² are in the form of arcuate blocks, being of like construction and each including a horizontally disposed flange 226; a semi-circular upstanding flange 223 at the inner edge; and a radially extending, horizontally disposed, outwardly projecting arm 224 adapted to be received in one of the openings 222 in the flange 218 and to project beyond the latter. The locking elements are disposed at opposite sides of the 10 cylindrical portion 214 of the member A² with the flanges 226 thereof received in the recess 220 and the flanges 223 arranged in spaced relation to the portion 214, with the outer faces thereof adjacent the arms 224 retained in abutting relation with the inner 15 face of the flange 218 by cotters 225 passing through the arms 224 and abutting the outer side of the flange 218. Upon reference to Figs. 5 and 6, it will be seen that when the 20 blocks are in the position above referred to they engage the upper surface of the member B² and overlap the flange 215 of the member A², holding the members A² and B² interlocked, upward movement of the blocks 25 being prevented by the flanges 226 engaging the over-hanging ledge 221 of the flange 218, and inward displacement being prevented by the pins 225. The blocks G² are of such a 30 width that they may be easily inserted from above into the recess 219.

The members A² and B² may be assembled and interlocked in the following manner. With the flange 215 disposed above the upper edge of the flange 218, blocks G² are 35 placed upon the flange 215 in embracing relation and in contact with the cylindrical face of the projection 214 and with the arms 224 in vertical alinement with the respective openings 229 of the flange 218. The 40 members A² are then lowered together with the blocks into the opening 219, the outer edge of the blocks clearing the inner edge of the flange 218 and the arms 224 entering the 45 openings 229. When the parts have been 50 thus assembled and the flange 215 is resting

upon the members B² with the upper surface flush with the upper surface of the latter, the members A² and B² are interlocked by sliding the blocks G² outwardly to the position shown in Fig. 5, the cotters 225 55 being inserted in the arms 224 to retain the blocks in position. In separating the members A² and B² the reverse procedure takes place, as will be observed.

I have herein shown and described what 60 I now consider the preferred manner of carrying out the invention, but the same is merely illustrative and I contemplate all changes and modifications that come within the scope of the claims appended hereto. 65

I claim:

1. In car construction, the combination with a truck bolster; of a center bearing plate rigidly secured to the truck bolster, said plate being provided with an upstanding flange; a body bolster; a center bearing plate rigidly secured to the body bolster, said plate being provided with a downwardly projecting portion adapted to bear on said truck bolster plate and having a horizontally 70 disposed annular flange; a plurality of vertically removable blocks interlocked with said upstanding flange and overlying said annular flange for detachably connecting said plates; and means for maintaining said 75 blocks in interlocking engagement.

2. In car construction, the combination with a truck bolster; of a center bearing plate rigidly secured to the truck bolster; a body bolster; a center bearing plate rigidly 80 secured to the body bolster, one of said plates being provided with an upstanding, continuous, flange and the other of said plates being provided with a cylindrical projection having an outwardly extending annular 85 flange thereon; a plurality of locking blocks overhanging said annular flange; and a plurality of pins interlocking with the blocks and the upstanding flange for detachably 90 securing the locking blocks to the upstanding 95 flange of the truck bolster.

In witness that I claim the foregoing I have hereunto subscribed my name this 16th day of June, 1923.

JOHN F. O'CONNOR.
